UNITED STATES PATENT OFFICE.

EDWARD S. STADELMAN, OF CHICAGO, ILLINOIS.

ADJUSTABLE SHAKING SCREEN.

Application filed August 3, 1922. Serial No. 579,401.

To all whom it may concern:

Be it known that I, EDWARD S. STADELMAN, a citizen of the United States, residing in the city of Chicago, in the county of 5 Cook and State of Illinois, have invented a new and useful Adjustable Shaking Screen, of which the following is a specification.

My invention relates to shaking screens, and more particularly to shaking screens 10 which are adapted for the screening of various materials, such as coal, ore, coke, sand, gravel and stone, etc. The object of my invention is to provide an improved, strong and adjustable construction.

15 In the accompanying drawings—

Fig. 1 is an end elevation, partially broken away, of a screen embodying my invention;

20 Fig. 2 is a side elevation of the same, also partially broken away;

Fig. 3 is an end elevation partially broken away, of a modification; and

Fig. 4 is an end elevation of the same.

25 My construction permits of a wide range of adjustment in the movement of the screen and this, in connection with certain other features, gives a better screened product than has been heretofore possible. This refinement of product and the simplicity of 30 design of the machine, combined with the adaptability obtained from the wide range of adjustability, are the principal advantages of my invention.

The main frame of my shaking screen 35 consists of two side frames K connected at the bottom by cross beams S and S'. I prefer to make each side frame of a flanged casting, though it can be built up from structural iron or wood if desired. At the 40 top of these side frames K are mounted bearings A for the main drive shaft B, on one end of which is mounted a pulley D.

On the drive shaft B are eccentrics C, C, 45 preferably situated next to each main bearing A, and hanging on these two eccentrics are hanger rods E, E, whose lower ends support the screen shaft I. Mounted on this shaft I by means of pivot bearings J is the screen frame G. This screen frame G is 50 also supported at each end by two links, L, L, reaching from the front and back edges of the screen frame to a point on the upper part of the hanger rod E. In each of these links near the screen frame end there is a row of holes O, O, through which a pin Q can be inserted into the screen frame to

fasten the screen frame and link together. By varying the connection by means of these series of holes, the slope of the screen frame can be adjusted at will. In the frame G is 60 laid a perforated screen plate G'.

On each end of the screen shaft I, I pivot a feed link F. The other end of this link is pivotally fastened to one or other of a series of holes 1, 2, 3 in the side frame of the machine by a pin M. These holes 1, 2, 3 are 65 preferably above the level of the screen shaft. I may also provide counterbalance wheels D' on the drive shaft for the eccentrics.

In operation the material to be sorted is fed onto the sloping screen at the upper end and the reciprocatory movements of the screen propel the oversize material along the surface of the inclined screen to the lower 75 edge, while the small sizes are shaken through the screen. In my construction when the drive shaft B is turned, the eccentrics C, C, impart a substantially vertical reciprocatory movement to the screen shaft I 80 through the hanger rods E, while the links F impart a longitudinal feeding movement to the screen which advances the material along the same. The precise curvilinear figure described by a point on the screen is 85 variable, depending upon the position of pin M and the length of the feed link F and its point of attachment to the screen. The horizontal component of the motion of the screen may thus be varied with corresponding 90 variation of the feed of the material along the screen at each cycle of movement. Adjustment of the inclination of the screen plate further increases the adaptability of the machine. If there is only one screen in 95 the machine the counterbalance wheels D' make the operation of the machine more even.

In Fig. 4 I show a form of my screen in which the counterbalance wheels are 100 eliminated and two screens are suspended from the one drive shaft—one below the other. There are two sets of eccentrics, one set for each screen, and they are set 180° apart, of course, so that the two screens thus 105 balance each other in a measure. By using different meshes in the two screen frames and feeding onto the upper screen as before, I may obtain three screenings, one size 110 through the bottom screen and one size delivered from the surface of each of the screen plates.

It is obvious that the length of the link F may be varied, and its point of attachment to the screen shifted, to accommodate the change in length of the link, toward 5 one edge or the other of the screen instead of being placed at the suspension axis I as shown. Such a variation in the point of connection of the link F to the screen makes it possible to further vary the throw of the 10 screen and the travel of the material on the screen.

The details of construction shown are merely exemplary of the underlying thoughts of my invention, which may be 15 embodied in various structures without departing from what I claim as my invention.

I claim:

1. A shaking screen having a drive shaft, a screen frame, and means suspending said 20 screen frame from said shaft and tending to impart movement to the screen frame from the drive shaft, in combination with adjustable means restricting said screen frame to curvilinear motion and other means 25 adjustably controlling the inclination of said screen frame.

2. A shaking screen having a drive shaft, a screen frame and means suspending said screen frame from said shaft and tending 30 to impart substantially vertical movement to the screen frame from the drive shaft, in combination with two independently adjustable means, one restricting said frame

to curvilinear motion and the other controlling the inclination of said frame. 35

3. A shaking screen having a drive shaft, eccentrics on said shaft, suspension means mounted on said eccentrics, and a screen frame tiltably suspended from said suspension means, in combination with adjustable 40 links governing the tilt of said screen frame, and radius links pivotally connected to the suspension axis of said screen frame and restricting the latter to curvilinear motion.

4. A shaking screen having a drive shaft, 45 a screen frame and means suspending said screen frame from said shaft and tending to impart substantially vertical movement to the screen frame from the drive shaft, in combination with two independently adjustable 50 means, one restricting said frame to curvilinear motion and the other controlling the inclination of said frame, and counterbalance wheels on said shaft.

5. A shaking screen having a frame, a 55 drive shaft, eccentrics on said shaft and two screen frames in combination with means suspending said screen frames so as to counterbalance each other and impart movement to each, and independently ad- 60 justable means for each screen frame, each restricting its frame to curvilinear motion.

In testimony whereof I have signed my name to this specification.

EDWARD S. STADELMAN.
